237,901

MIXING MACHINE

Keith Moran, 61 Guildford Road, Colchester, Essex, England, and Douglas Alan Michael Elston, 22 Desenfans Road, London SE. 21, England

Filed Sept. 21, 1973, Ser. No. 399,518

Term of patent 14 years

Int. Cl. D15—04

U.S. Cl. D55—1 D

Fig. 3.

FIG. 1 is a perspective view of the front and one side of the mixing machine;

FIG. 2 is a perspective view of the back and one side of the mixing machine; and

FIG. 3 is an elevational view from the front of the mixing machine, along the axis of the mixing drum.

The mixing machine is intended particularly but not exclusively for mixing cement.

We claim:

The ornamental design for a mixing machine, substantially as shown and described.
